UNITED STATES PATENT OFFICE.

JOHN B. BRADY, OF SOMERSET, MARYLAND, ASSIGNOR TO BRANDES LABORATORIES, INC., OF NEWARK, NEW JERSEY, A CORPORATION OF NEW JERSEY.

BINDING POST.

Application filed July 13, 1923. Serial No. 651,312.

My invention relates broadly to electrical circuit connectors, and more particularly to a protective connecting device for electrical circuits.

5 One of the objects of my invention is to provide an attachment for binding posts on electrical apparatus which it is desired shall be protected against excessive electrical currents.

10 Another object of the invention is to provide an inexpensive construction of adapter which may be secured to various standard forms of binding posts, which adapter serves as a protective device against the passage of 15 excessive currents in the circuits connected with the binding posts.

Another object of the invention is to provide an adapter for binding posts which carries a fuse through which the current must 20 pass to reach the electrical circuit connected with the binding post, the fuse being of such value that it will be ruptured in the event that the energy being supplied to the electrical circuit connected with said binding post 25 should rise beyond a given limit.

A still further object of my invention is to provide a device applicable to the filament lighting binding post usually provided upon a radio receiver to protect the electron tubes 10 used in the radio receiving circuits from excessive filament currents to which they might be subjected by mistake in choosing a safe filament potential.

My invention will be more clearly understood from the following specification by reference to the accompanying drawings, in which:

Figure 1 shows the application of my invention to any standard electron tube radio 10 receiving apparatus; Fig. 2 is a perspective view illustrating in outline any type of electron tube radio receiving apparatus showing the protective devices of my invention applied to the filament circuit binding posts 15 on the panel of the radio receiver; Fig. 3 is a cross sectional view through a binding post showing one form of fused adapter screw threaded over the post; Fig. 4 is a cross sectional view taken on line 4-4 of Fig. 3 showing one method of securing the auxiliary binding post to the extremity of the fused adapter; Fig. 5 is a view partially

in cross section showing a modified construction of fused adapter; Fig. 6 is an enlarged fragmentary view showing a form of brush 55 carried by the insulating bushing of the adapter shown in Fig. 5 which is used for completing an electrical connection between the fusible conductor and the binding post upon which the adapter is secured; Figs. 7 60 and 8 show in cross section and in side elevation respectively another modified construction of adapter for a binding post; Figs. 9, 10 and 11 illustrate a protective device for binding posts wherein the fusible member is 65 in the form of a removable element which may be renewed when ruptured by excess current; Fig. 12 is another modified form of a renewable fused unit for binding posts; and Figs. 13 and 14 show another form 70 which my invention may take.

With the increasing use of radio receiving apparatus by the general public in the reception of radio broadcast news, concerts, church services, music, and lectures, various 75 types of electron tubes have become popular, many of which require different values of filament potential for lighting the cathodes. It is often confusing to those inexperienced in the art to determine the proper potential to be applied to the filament lighting 80 circuit for a given type of tube. A large number of sets now employ electron tubes whose filament circuits are supplied from the ordinary dry cell, the filament electrodes 85 having a rating of 0.25 or .060 ampere at a voltage range of 1.1 to 5 volts and 3 volts respectively. It is not unusual for an inexperienced user of radio apparatus to so misconnect the binding posts carried on the 90 radio apparatus through hurry or mistake that the potential from the B battery or other undesired high potential might by chance find its way across the filament circuit and thereby instantaneously burn out 95 expensive tubes.

By my present invention I avoid the destruction of electron tubes by providing an inexpensive construction of fused adapter which may be screwed over the ordinary binding posts already provided on the set and then receive the usual cap screw which may have been previously removed from the standard binding posts on the set, the protecting fuse 100

wire being carried in or by the adapter and interposed between the binding post on the set and the cap screw on the adapter. The adapter of my invention is extremely inexpensive and simple of manufacture, and may be produced on a quantity production basis at reasonable cost. The fusible member on the adapter is also capable of renewal for the purpose of replacement after rupture on occasion of passage of excess current.

Referring more particularly to the drawings, the wiring diagram in Fig. 1 is illustrative of the application of my invention as a protection for the filament circuits of electron tubes in a radio receiver. Reference character 1 indicates a standard form of regenerative electron tube receiver connected with an antenna system. The electron tube 2 is connected to rectify the incoming signal energy and electron tubes 4 and 5 function as audio frequency amplifiers for the rectified energy. The filament circuit for electron tube 2 is represented at 6. The filament circuit for the tubes 4 and 5 has been shown at 7. The terminals for the filament circuit of tube 2 are represented at 10 while the terminals for the filament circuit 7 are shown at 11. For the purpose of illustrating the application of my invention I have shown separate batteries A_1 and A_2 . I provide fusible members 8 and 9 in the filament circuits in such position that energy cannot pass from any external source to the filament circuits without traversing the fusible links 8 and 9.

These fusible members are constructed so that they are readily adapted to any form of standard binding post already employed on a cabinet containing the radio apparatus in such position that the ordinary binding post leading to the filament circuits interior of the cabinet are placed in circuit with the external source with the fusible member interposed between the external source and the filament circuits. In Fig. 2 I have shown a cabinet 3 which contains a two stage electron tube amplifier with the tubes connected as represented for the tubes 4 and 5 in Fig. 1. The input circuit terminates at binding posts 15 and 16. Binding posts 17 and 12 are provided for the B battery connection. Binding posts 11 are the terminals for the filament circuits. The cap screws are removed from the binding posts and small adapters carrying fusible members 9 screwed over the binding posts in place of the cap screws and then the cap screws 12 and 14 are replaced upon an auxiliary binding post carried by the adapters. The addition of the adapters slightly increases the height of the post but not to such an extent that the hinged cover of the cabinet cannot be closed in the usual manner. The additional height of the filament circuit binding posts as compared to the height of the adjacent binding

posts serves as an additional means for readily distinguishing the filament circuit terminals.

The fusible members may be constructed in various forms. I have shown a number of these forms in Figs. 3-14. The usual binding post 11 is shown positioned upon panel 18 with the shank 21 of the binding post extending through the panel 18 to provide a permanent connection for the filament lighting circuit interior of the cabinet 3 containing the radio apparatus. A pin 22 is usually provided on the binding post for centering and preventing rotation of the post. In Fig. 3 an annular insulating bushing 23 contains interior screw threads corresponding to the screw threads on the head of the binding post at 20. An auxiliary binding post 24 corresponding to the main binding post 11 is carried by the insulating bushing 23. This is accomplished in Fig. 3 by means of a short shank 25 depending from the binding post 24 and secured with respect to the insulating bushing 23 by means of a pin 26. A short metallic ring 29 is forced over the end of the insulating bushing 23 such that when the insulating bushing 23 is threaded over the head of the binding post 20, the ring 29 makes electrical contact with the binding post 11. I connect the fusible member 9 between the ring 29 and the connection 27 in the binding post 24. The cap screw 14 which was removed from the head of the auxiliary binding post 24 anchoring a wire 31 which connects with the external source of supply. It will be observed that electrical energy can only reach the binding post 11 by passing through the fusible member 9.

The fusible member 9 may also be connected with the binding post 11 by means of a brush member 32 in the form of a pin projecting from a lower edge of the insulating bushing 23 as shown in Figs. 5 and 6. The fusible member 9 may be protected by means of a sleeve 33 slipped over the outside of the adapter.

Connection may also be made with the head of the binding post 20 by means of a metallic bushing 34 molded into the insulating bushing 23. The fusible member 9 may then be interposed between the metallic bushing 34 and the binding post 24 by connection at 37 and 36 respectively. A sleeve 35 may then be slipped over the outside of the adapter.

The fusible member may be constructed as a removable unit as represented in Figs. 9-11. A short insulating tube 41 may be provided with metallic caps 39 and 40 at opposite ends thereof, the fusible member 9 being connected between the caps 39 and 40 as indicated at 38. The renewable unit 38 is then clamped between the head 20 of

binding post 11 and the bottom wall of binding post 24 forming a closure for the end of the insulating bushing 23. Should this fuse be ruptured the unit 38 may be discarded and a perfect unit inserted.

In Fig. 12 the fusible member 9 is in the form of a small spiral centered in a washer 43 which is clamped upon the head 20 of the binding post 11 by screwing down the insulating bushing 23. The other end of the fusible member 9 is clamped by means of the metallic sleeve 42 which carries the binding post 24 and is forced over the insulated bushing 23.

In Figs. 13 and 14 a binding post 45 has been indicated supported in panel 44. A removable member 46 having a metallic eyelet 47 in one end and a binding post 48 in the other end is arranged to be slipped over the head of the binding post 45. The fusible member is interposed between the eyelet 47 and the binding post 48. A connection 50 may then be made upon binding post 48 and the energy passed to the main binding post 45 by way of fusible member 9.

While I have illustrated this fusible connector in connection with electron tubes it will be clear that it may be used for binding posts anywhere in the electrical art where it is desired to protect delicate instruments. The size of the fuse is selected to provide the proper factor of safety for the tubes, sufficient variation being allowed to take care of such variations as might be imposed upon the circuit. It is also clearly understood that various sizes of fusible elements must be supplied to protect different values of load.

While I have described my invention in certain limited embodiments and illustrated only a few of the many forms which it may take it is to be understood that modifications in details may be made and that I intend no limitations upon the invention other than are imposed by the scope of the appended claims.

What I claim and desire to secure by Letters Patent of the United States is as follows:

1. An electrical connector comprising in combination a screw threaded binding post, an insulating rotatable member arranged to be screw threaded down upon said post, a binding post carried by said member and a removable fuse member arranged to be clamped between said binding posts when said rotatable member is screwed down on said first mentioned post, one end of said

fuse member connecting with said first mentioned binding post and the other end connecting with said last mentioned binding post.

2. An electrical connector, comprising in combination a binding post, an insulating member arranged to be inserted over said binding post, a second binding post carried by said insulated member, a fuse member arranged to be clamped between said binding posts whereby electrical energy must pass through said fuse member in reaching said first mentioned binding post.

3. An electrical connector comprising in combination a binding post, an insulating tubular member arranged to be inserted over said binding post, said member having a length substantially greater than the height of said binding post, a second binding post carried in one end of said member forming an end closure for said member, a fuse member arranged to be clamped between said binding posts whereby electrical energy must pass through said fuse member in reaching said first mentioned binding post.

4. An electrical connector comprising in combination a binding post, an insulating tubular member arranged to be inserted over said binding post, said member having a length substantially greater than the height of said binding post, a second binding post carried in one end of said member forming an end closure for said member, a fuse member arranged to be clamped between said binding posts, said fuse member comprising an insulated tube, a metallic cap on each end thereof, said fuse being connected between said caps, one of said caps contacting with one of said binding posts and the other of said caps contacting with the other of said binding posts whereby electrical energy must pass through said fuse member in reaching said first mentioned binding post.

5. An electrical connector comprising in combination a screw threaded binding post, an insulating screw threaded tubular member having a length greater than the height of said binding post, an auxiliary binding post carried in the upper end of said tubular member, a fuse supported by said bushing, a pair of members connecting said fuse to both of said binding posts, said auxiliary binding post being so arranged in said member that it is at all times spaced from said first mentioned binding post.

JOHN B. BRADY.
